UNITED STATES PATENT OFFICE.

JOHN H. KEYS, OF DAYTON, OHIO, ASSIGNOR TO THE DAYTON IRRIGATION COMPANY, OF DAYTON, OHIO, A CORPORATION OF OHIO.

SPRINKLER.

Application filed August 7, 1922. Serial No. 580,257.

My invention relates to water distribution and more particularly to an automatic sprinkler of the rotary type. The invention pertains to a rotary sprinkler having pivoted or folding jet arms carried by a sprinkler head provided with a discharge nozzle rotating in unison with said arms the structure being vertically movable into and out of operative position by variations of the water supply pressure, the sprinkler head being retractible into a sunken receiver or container within which the sprinkler is concealed when not in use. The construction is such that upon the admission of water under pressure to the sprinkler the latter is bodily elevated out of its sunken receptacle or container the jet arms being simultaneously actuated to the extended positions, whereafter the influence of the discharging jets of water may serve to rotate the sprinkler head and with it the auxiliary nozzle. When the pressure is reduced the sprinkler settles by gravity into its receptacle the jet arms being projected to an upright or substantially vertical position by their engagement upon the rim of the receiver or receptacle and the latter is closed by a lid supported upon the sprinkler head.

The object of the invention is to simplify the structure as well as the means and mode of operation of such automatic sprinklers, whereby they will not only be cheapened in construction, but will be more efficient in use, positive in operation, uniform in action, easily controlled and unlikely to get out of repair.

A further object of the invention is to provide improved means for mounting the adjustable propeller arms or jet arms for such sprinkler head.

A further object of the invention is to provide an improved mounting for the sprinkler head, whereby it may be easily actuated to and from operative position under the influence of fluid pressure control.

A further object of the invention is to provide improved rotary bearings for the revolving sprinkler, and to provide an improved method of mounting the rotary sprinkler head within its bearing whereby the wear will be minimized and the durability of the sprinkler head and its bearing materially increased.

With the above primary and other inci-

dental objects in view as will more fully appear in the specification, the invention consists of the features of construction, the parts and combinations thereof, and the mode of operation or their equivalents as hereinafter described and set forth in the claims.

In the accompanying drawings, wherein is shown the preferred, but not necessarily the only embodiment of the invention, Fig. 1 is a perspective view of the automatic sprinkler forming the subject matter hereof, illustrating the installation in a lawn with the sprinkler shown in its elevated or operative position. Fig. 2 is a top plan view of the sprinkler with its jet arms or propeller arms extended. Fig. 3 is a vertical sectional view of the sprinkler in its retracted position. Fig. 4 is a vertical sectional view of the sprinkler head and its rotary bearing. Fig. 5 is a detail sectional view at right angles to that of Fig. 4, illustrating the mode of connecting the pivoted jet or propeller arms. Fig. 6 is a vertical sectional view of a modification of the sprinkler head and bearing. Fig. 7 is a sectional view at right angles to Fig. 6 illustrating the mode of interconnecting the flexible or pivoted propeller arms.

Like parts are indicated by similar characters of reference throughout the several views.

The automatic sprinkler forming the subject matter hereof is intended to be permanently installed in gardens, lawns, parks upon golf courses and analogous locations and is supplied with water under pressure through underground pipes or conduits leading from a suitable source of supply. When inoperative the sprinkler is not only concealed or masked, but the receiver or container for the sprinkler is automatically closed to protect the sprinkler and exclude dirt. If so desired the closure of the container or receiver may be adapted to carry a section of sod or turf, which will agree with the surrounding surface and so effectively mask or conceal the sprinkler receiver.

In the accompanying drawings, 1 is the sunken receiver or enclosure for the sprinkler head, which is embedded in the earth. For convenience and economy of manufacture, this receiver 1 may be merely a short section of two inch pipe interconnected at

its lower end with an ordinary reducing pipe coupling 2, with which is engaged an upright section 3 of the water supply conduit. This section 3 is preferably a one inch pipe screw threaded into the reducing coupling 2 at its lower end. The screw threaded engagement of the larger pipe section 1 with the coupling 2 affords a limited range of adjustment by which the upper or open end 10 of the pipe section forming the receiver for the sprinkler head may be brought into flush relation with the surrounding lawn surface. Telescopically mounted within the upright supply section 3 is a reciprocatory tubular stem 4, having at its lower end an enlarged head 5, which approximately fits the interior of the upright portion of the conduit 3 forming therein a piston head subjected to the pressure of the water. To afford a suitable bearing for this telescopic stem 3, the reducing coupling 2 is preferably partially filled with a body 6 of Babbitt metal or other material suitable for such a bearing, such babbitted bearing being bored out to 25 fit the reciprocatory stem 4. In the present instance, a drain hole 7 has been provided extending through this body of bearing material 6, and communicating with a collecting channel 8 in the upper face of the bearing 30 6.

The peripheral flange or piston head 5 of the reciprocatory stem may be provided with suitable packing rings or an annular collar of packing material intermediate the 35 periphery of the head and the interior wall of the pipe section 3. However, in practice this construction has not been found necessary under ordinary conditions of use.

The distributor head and actuating mechanism are carried by the reciprocatory stem 4. Secured to the upper end of the reciprocatory stem 4 is a bearing sleeve 9. This bearing sleeve 9 is counter-bored to form an interior bearing shoulder or thrust bearing 45 10 with which co-operates a peripheral flange 11 or enlarged head upon the lower end of a rotary hollow trunnion 12. Anti-friction collars or washers preferably of German silver or other suitable material 50 are interposed between the enlarged head or peripheral flange 11 and the thrust bearing or shoulder 10. After assembling the hollow trunnion 12 within the bearing sleeve 9 a bushing 13 is introduced into the screw threaded extremity of the sleeve 9 beyond the head of the trunnion and the upper end 55 of the reciprocatory stem 4 is screw threaded within such bushing 13.

Carried upon the upper end of the hollow trunnion 12 is a distributor head or cap 15, having an inclined discharge nozzle 14 communicating with the interior of the head. Pivotal connected to opposite sides of the distributor head or cap 15 are jet or propeller arms 16, which when in operative

position are inclined outwardly in opposite directions and when in inoperative position are retracted to a substantially vertical position whereby they may enter wholly within the receiver 1. These jet arms 16 have discharge orifices at the extremities thereof. The orifices 17 are located at approximately an angle of forty-five degrees in relation with the plane of rotation whereby the reaction of the jet not only propels the sprinkler head revolvably upon the hollow trunnion 12 but will also propel the jet arms outwardly to their extreme operative position. That is to say, the discharge of the jet orifices 17 will initially propel the pivoted arms 16 80 from their upright or retracted position to their extended position in the event that the arms do not fall by gravity and will thereafter propel the entire distributor head revolvably upon the trunnion 12. In addition to 85 the jet orifices 17 the propeller arms may be provided with additional orifices in the extreme ends thereof. To limit the movement of these propeller arms 16 to and from operative engagement there are provided short stop arms 18, projecting into the plane of oscillation of the arms 16 and limiting the arms in approximately upright position and other arms 19 downturned over the sides of the cap or head 15 with their extremities 90 projected outwardly to form rests for the arms 16. Stop arms 18 and downwardly and outwardly projecting rest arms 19 are preferably stamped from a single piece of sheet metal and secured to the top of the distributor head or cap 15 by screws 20 or by other suitable means. However, any other form of stops may be used as for instance, merely lugs or studs projecting from the head 15 at suitable points.

Various modes of attachment of the pivoted arm 16 may be employed. In Fig. 5 there is shown a construction wherein bushings 21 are threaded in the opposite sides of the cap or head 15. These bushings are 110 counter-bored on their inner sides to form seats for hollow trunnion studs 22. These studs are introduced from the inner side of the bushing with their screw threaded extremities projecting outwardly from the 115 bushing and into engagement with heads 23 upon the inner ends of the jet or propeller arms 16. In assembling these parts the trunnion studs 22 may be introduced into the bushing 21 and the latter screwed into the threaded openings in the side of the head 15 from the exterior. By introducing a thin flat blade such as the end blade of a screw driver or piece of flat or sheet metal 120 suitably proportioned into engagement with the slot 24, of the head of such hollow trunnion, which slot will in such event be turned parallel with the axis of the head 15, these hollow trunnions may be held stationary, while the head 23 of the propeller arms is 125

tightly screwed upon the projecting end of the trunnion stud. It will be understood that these connections are effected before the head 15 is attached to the upper end of the hollow trunnion stud 12. This permits the screw driver blade or other implement to be introduced through the open end of the head or cap 15 into engagement with the slotted head of the hollow trunnion stud, previously turned into alinement with each other and with the axis of the cap. In this construction the trunnion studs 22 oscillate in their bearing in the bushing 21. In Fig. 7 there is shown a modification of this construction wherein the trunnion stud is stationary and the head of the propeller arm oscillates thereabout. In this construction the heads 25 of the propeller arms 16 are counterbored to form a seat or shoulder 26 at their inner ends with which engages the head of the hollow trunnion stud 27. This trunnion stud 27 is screw threaded into openings in the side of the upper end of the revolute hollow trunnion 12. In this case the trunnion 12 is closed at its upper end and the propeller arms are connected directly to the trunnion in lieu of the head or cap 15. The outer ends of the propeller arms 25 are closed by removable closure plugs or caps 28, the removal of which affords access to the trunnion stud 27. Fixedly attached to the head or cap 15 or to the closed end of the trunnion 12 as shown in Fig. 7 is a strut or standard 29 which carries at its upper end a closure disc 30 forming a lid or closure for the receiver 1. The open end of this receiver 1 is preferably beveled or inclined as at 31 to receive the lid 30.

In order that the reciprocatory stem 4 may be held against rotation while the bearing sleeve 9 and bushing 14 are tightened thereon and also to afford means for the recovery for the reciprocatory stem in the event that the sprinkler is removed therefrom and the stem allowed to drop within the receiver there is provided a transverse pin 32 extending through the upper end of the stem 4 which by its engagement with the bearing body at the lower end of the receiver will limit the descent of the stem. This transverse pin 32 also affords means which may be engaged by a hook or wire loop to lift the stem 4 in the event that it has been dropped while the sprinkler is removed for repairs or examination. To increase the durability of the structure, the bearing sleeve 9 is preferably though not necessarily provided with a lining or core of Babbitt metal or other such material as shown by the condensed shading at 33. In practice the sleeve 9 is either sand cast or die cast and a body of Babbitt metal is poured therein to afford the requisite bearing for the hollow trunnion stud 12. When in operation

the sprinkler rotates at a very rapid rate under the influence of the jets discharged from the propeller arm distributing such jets of water over a wide range. This discharge of the propeller or jet arm is supplemented by the auxiliary discharge nozzle 14 carried centrally upon the sprinkler and rotating in unison with the jet arms. Cross reference is made to co-pending application, Serial No. 580,256 filed of even date here-with which has since matured into Patent No. 1,605,242 issued Nov. 2, 1926.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention is therefore claimed in any of its forms or modifications within the legitimate and valid scope of the appended claims.

Having thus described my invention, I claim:

1. In a disappearing sprinkler, a vertically movable nozzle, fluid pressure means for raising and lowering the nozzle, yielding jet propulsion arms for the nozzle, an enclosure for said nozzle when lowered into which the arms are yieldingly retracted, and a closure lid fixedly attached to the nozzle for up and down movement therewith.

2. In a sprinkler, a rotary head having substantially radially disposed distributor arms, said arms being foldable to and from a position substantially parallel with the axis of the rotary head, means for raising and lowering the sprinkler and means for automatically adjusting the arms in unison with the vertical movement of the sprinkler.

3. In a sprinkler, a rotary head, a plurality of substantially radially disposed distributor arms carried by said head, means for raising and lowering the sprinkler, and means for automatically retracting and extending the arms in unison with vertical adjustment of the sprinkler.

4. In a sprinkler, a rotary head, a plurality of relatively adjustable distributing nozzles, retractile and extensible in relation with the axis of rotation of the head, and a sunken receptacle into which the rotary head is retractile when the adjustable arms

are contracted, and beyond which the nozzles project when in extended position.

5. In a sprinkler, a vertically movable distributor head, a plurality of nozzles yieldingingly connected with said head, and means engaged by the nozzles upon vertical adjustment of the head for adjusting the nozzles.

6. In a sprinkler, a rotary head, a plurality of automatically adjustable jet arms 10 flexibly connected with the head for adjustment to positions angular to the plane of rotation, a vertically adjustable mounting for the sprinkler device, and a sunken receptacle into which the head and arms are depressed by the vertical retraction of the mounting, said arms when in operation extending beyond the limits of the receptacle.

7. In a sprinkler, a rotary head, a plurality of substantially radially disposed jet 20 arms, a receiver into which the sprinkler is retractible, said receiver being of less radius than the spread of said arms whereby the arms engage the edge of the receiver upon retraction of the sprinkler, said arms being 25 yieldably connected whereby they will accommodate themselves to the receiver, and fluid pressure control means governing the movement of the sprinkler into and out of the receptacle.

8. In a sprinkler, a collapsible distributor comprising a head and a plurality of jet arms carried thereby, a receiver for the distributor, said arms being foldable for entrance into the receiver in compact form, 35 and means for raising and lowering the distributor out of and into the receiver.

9. In a sprinkler, a fluid pressure operated rotor, a discharge nozzle fixedly carried by the rotor and rotating in unison therewith, and a plurality of extensible and retractible 40 jet arms connected with the rotor and rotating in unison with the nozzle, said arms being maintained in their extended positions during the period of discharge and being retractible to approximately parallelism to reduce the sprinkler to compact form for storage, and means for automatically controlling the adjustment of the flexible arms.

10. A sprinkler including in combination 50 a central tubular stem rotatably mounted to turn upon a vertical axis, a plurality of jet arms adjustably connected to the tubular stem and receiving their water supply therefrom, and means for automatically retracting and extending the jet arms toward and from the stem by variation of the water pressure.

11. A sprinkler including in combination, 60 a central tubular stem mounted for vertically reciprocatory movement, a plurality of jet arms adjustably connected to the tubular stem for rotary movement about the axis of said stem, and receiving their water supply therefrom, and means for effecting relative 65 adjustment of the arms toward and from

the stem in unison with vertical adjustment of the latter.

12. A sprinkler including a central tubular stem, a plurality of jet arms adjustably connected with the tubular stem, and a housing into which the stem and jet arms are retractible, said arms being capable of extension beyond the lateral walls of the housing for operation, and means for automatically adjusting said sprinkler into and out 75 of the housing.

13. A sprayer including in combination a vertical tubular support having means for connection with a water supply, repulsion jet arms pivotally mounted thereon and receiving their water supply therefrom, said tubular support being vertically adjustable under influence of water pressure and means whereby the arms are automatically adjusted about their pivotal connections in unison 85 with the vertical adjustment of the tubular support and an additional discharge nozzle located above the level of operation of the jet arms and arranged in an upwardly and outwardly inclined radial position and rotating in unison with the jet arms.

14. A sprinkler including in combination a hollow revolvably mounted head, to which water is delivered under pressure, a discharge nozzle carried by the head and projecting angularly in relation with the axis of rotation, a vertically reciprocatory mounting for said head, a casing into which the head is retractable by the reciprocation of the mounting, said head being revolvble 100 under influence of the water being discharged and adjustable jet arms carried by said head and extending radially beyond the periphery of the receptacle when said head is in its operative position.

15. A sprinkler including a central vertically adjustable tubular stem to which water is supplied under pressure, a revolvble discharge nozzle mounted at the top of said stem and discharging in a substantially radial direction upwardly and outwardly inclined to the axis of rotation, a casing into and out of which the discharge nozzle is movable by the vertical adjustment of said stem and adjustable reaction jet arms also mounted upon said stem and deriving their water supply therefrom, said arms extending in approximate radial directions beyond the periphery of the casing when such stem and nozzle are elevated, said arms being retractable toward the axis of rotation of said nozzle to permit the descent of the stem and nozzle into the casing, said jet arms being located below the level of the discharge nozzle and operatively connected therewith for 110 positively rotating the discharge nozzle.

16. In a sprinkler construction, a receptacle, a sprinkler head to be stored in said receptacle, a series of revolvble jet arms carried by the head and mounted for 130

- spreading movement beyond the sides of said receptacle, the arms being extended beyond the dimensions of the receptacle and being retracted within the dimensions of the receptacle preparatory to storage of the head and arms therein in accordance with the admission and arrest of water under pressure to said sprinkler.
17. A sprinkler including a central tubular water supply stem, a plurality of jet arms carried thereby and rotating about the axis of said stem, said arms being capable of spreading and contracting movement relative to the stem and means controlling such movement effecting the spreading of the arms upon the admission of water under pressure to the sprinkler, and the retraction

of the arms when the pressure of water is relieved.

18. A sprinkler including a series of radially disposed jet arms revolving about a common axis, means for supplying water thereto under pressure, said arms being flexibly mounted for spreading and contracting movements, the spreading of the series of arms being effected upon admission of the water pressure to the sprinkler and the contraction of the series of arms being effected when the water pressure to the sprinkler is reduced.

In testimony whereof, I have hereunto set my hand this 1st day of August, A. D. 1922.

JOHN H. KEYS.
